MOTOR TRAIN

Alan R. Cripe, Chagrin Falls, Ohio, assignor to The Chesapeake and Ohio Railway Company, Cleveland, Ohio, a corporation of Virginia

Application August 16, 1955, Serial No. 37,675

Term of patent 14 years

(Cl. D66—1)

FIG.5

FIG. 6

FIG. 4

FIG. 9

Fig. 1 is a fragmentary side view of the power unit of the motor train and one of the cars articulated thereto, showing my design;

Fig. 2 is a side view of the opposite end of the motor train with the power unit and a car articulated thereto;

Fig. 3 is a top view of Fig. 1 showing the cab of the first power unit;

Fig. 4 is a front view of said power unit;

Fig. 5 is an enlarged cross-sectional view along the line 5—5 of Fig. 1, showing the outline of the car;

Fig. 6 is a top view of a power unit with the couplings open;

Figs. 7 and 7a are fragmentary side views of the car units of the motor train;

Fig. 8 is a side view of the entire train; and

Fig. 9 is an end view of the power unit with the coupling exposed.

I claim:

The ornamental design for a motor train, substantially as shown.
